CLAIM

The ornamental design for a power steering pump cover, as shown and described.

DESCRIPTION

FIG. 1 is a top, perspective view of a power steering pump cover showing my new design.

FIG. 2 is a front and side perspective view thereof with the cap and the nut of the power steering pump removed; FIG. 3 is a bottom perspective view thereof; and, FIG. 4 is a top plan view thereof.

The rear view is omitted and is not being claimed as part of the design.
